LIGHTING FIXTURE

Arthur Leichtung, Roslyn, N.Y.

Application February 11, 1958, Serial No. 714,525

3 Claims. (Cl. 240—78)

This invention relates to drop electric lighting fixtures and particularly to the shade-supporting means therefor.

Such fixtures are usually suspended by a cord or cable passing around a concealed pulley so that the fixture may be raised bodily or lowered to any selected height within a wide range. A switch is frequently provided on the fixture which customarily includes a plurality of individual lamp sockets.

The present invention contemplates the provision of simple, durable and inexpensive but efficient expandable and contractible means for so supporting the glass shade of such fixtures as to enable the user to lower and to tilt the shade quickly and easily when the lamps or other parts are to be cleaned, repaired or replaced, while the shade remains attached to the remainder of the fixture.

The invention further contemplates the provision of a frame having a fixed part symmetrical about the vertical axis of the fixture and a movable part and arranged around the lamp sockets for supporting the shade for convenient lowering and tilting while permitting ready access to the fixture switch and positively securing the shade in the normal raised or operative position thereof.

In the drawings,

Fig. 1 is a partial vertical sectional view and partial elevational view of the fixture, certain parts having been broken away for clarity, and the lowered and tilted position of the shade being shown by dash-dot lines.

Fig. 2 is a side elevational view thereof with parts broken away or in section and a somewhat different canopy shown above the reflector.

Fig. 3 is a top plan view of Fig. 1 but with the reflector and canopy omitted to expose the underlying parts.

Fig. 4 is a fragmentary expanded side elevational view of the connections between the shade and its support showing a modified form of the removable nut for positively maintaining the shade in the uppermost position thereof and used where no switch is provided on the fixture.

As shown, the cord or cable 10 is of the usual type employed in drop light fixtures, passing around a pulley requiring no illustration, and adapted to be extended or wound up to raise or lower the entire lighting fixture as a unit. The cable contains the wiring to the multiple lamp socket member 11, in which four interconnected sockets are shown, and is suitably connected to the fixture in a well known manner. The multiple socket member is arranged coaxially of the fixture in a generally horizontal plane and is fixedly connected to a suitable canopy as 12 (Fig. 1) or 13 (Fig. 2) by connections which serve also to support the downwardly convex reflector 14, part of which is shown in Figs. 1 and 2. Such connections include a bracket 15 of strip material and bent into generally inverted V-shape to form downwardly divergent legs connected at their upper ends by a somewhat widened and perforated end web 17, through which passes the nipple 16. The lower end portion of each leg is bent into a horizontal position and riveted as at 18 to the socket member 11. The lower end of the nipple

2

16 is headed and fixed permanently to the under face of the end web 17, the nipple projecting upwardly therefrom. The internally threaded connecting nipple 19 is screwed on to the lower nipple 16 and also on to the externally threaded upper nipple 20 which passes loosely through a hole in the fixed member 21 of the contractible and expandable shade-supporting frame soon to be described. The nipple 20 also passes through the central hole 22 of the reflector, through the canopy and into the locking nut 23. When said nut is tightened, the canopy reflector and fixed frame member 21 are pressed against the connecting nipple 19 and are fixed to the bracket 15 and socket member 11 as well as to the cable 10, and are raised and lowered as a unit on the retraction and extension of the cable.

As has been indicated, the frame is provided for so supporting the fixture shade, that the shade may readily be lowered and tilted when desired. The frame comprises the fixed frame member 21 and a movable frame member 29, the frame being in a generally vertical plane and encompassing a space in which the socket member 11 is arranged. Said member 11 is shown as arranged in a generally horizontal plane, but with the axes of the individual sockets thereof extending diagonally of the frame for convenience of access thereto. The fixed frame member 21 is preferably of strip material and is bent into the form of an inverted U, the upright parallel legs 24, 25 being connected at the upper ends thereof by the transverse web 26. Said legs are spaced far enough apart to pass around and to clear the sockets (Fig. 3) and any lamps held thereby, the frame enclosing a rectangular space and being coaxial with the socket member and the remainder of the fixture. To permit extension and contraction of the frame, a pin and slot connection is provided between the frame members.

In each of the legs 24, 25 is an upright slot 27 in which slides a pivot pin in the form of the rivet 28, which is fastened permanently to the movable U-shaped frame member 29 having upright parallel legs 30, 31 sliding vertically on the respective legs 24, 25 of the fixed frame member to the position indicated by the dash-dot lines of Figs. 1 and 2. The legs 30 and 31 are connected at the lower ends thereof by the horizontal web 32 having a central hole therein in which is fixed against movement the downwardly extending externally threaded nipple 33, which passes loosely through a central hole in the shade 34. Said shade is interposed between the web 32 of the movable frame member 29 and the shade-securing nut 35 on the relatively short nipple 33 and thereby moves as a unit with the movable frame member when permitted to do so. This occurs when the shade is disconnected from the socket member 11, to which it is normally connected in its operative or uppermost position, by connections soon to be described. When so disconnected, the pins 28 can slide downwardly in and to the bottoms of the slots 27, and the shade can also be swung about the pins 28 as pivots to provide ready access to the lamps and to the interior of the fixture.

The shade is detachably connected to the socket member 11 and thereby to the fixed parts of the fixture by the nut 36 which screws on to the externally threaded and relatively long nipple 37. Said nipple is fixed against movement to the horizontal connecting portion 38 of the generally V-shaped lower bracket 39, which is similar to the bracket 15 and is secured in a like manner to the under side of the socket member 11 as at 40. The smaller nipple 33 has a hole therethrough of sufficiently large diameter to permit the longer nipple 37 to telescope thereinto and to project therethrough downwardly enough for easy engagement with the shade-securing nut 36, which positively locks the shade in the uppermost or operative position thereof when the nut 36 is tightened.

In the form shown in Figs. 1 and 2, the nut 36 is hollow throughout and the switch knob 41 normally projects therethrough and can readily be operated when desired to open and close the switch 42 carried by the bracket 39 and controlling the current to the lamps 43. When the shade is to be lowered, the securing nut 36 is removed from the nipple 37, permitting the larger in diameter but shorter nipple 33, the nut 35, shade 34, frame member 29 and pins 28 to drop as a unit without disturbing the switch or the switch knob 41. To replace the parts in the normal operative positions thereof, the shade is raised enough to telescope the nipple 33 into the nipple 37 and until the former engages the web 38, whereafter the nut 36 is replaced on the nipple 37 and tightened. When the shade is raised, the pivot pins 28 move upwardly in the slots 27 to guide the shade into its uppermost position as it moves.

In the form shown in Fig. 4, the fixture switch and its control knob are omitted, and the shade-securing nut 44 is closed at the bottom. It will be seen that the shade is adequately held up by the nut provided for that purpose; that removal of the nut permits the shade and the associated parts to drop and tilt without danger of loss of control of the shade; that the frame support is inexpensive and durable and adapted for use with axially arranged sockets or sockets occupying relatively large areas without detracting from the symmetry of the fixture and that the fixture is well designed to carry out its intended purposes.

While certain specific forms of the invention have herein been shown and described, various obvious changes may be made therein without departing from the spirit of the invention defined by the appended claims.

I claim:

1. In an electric lighting fixture, a contractible and extensible frame comprising a movable U-shaped frame member having parallel upright legs, a fixed frame member of inverted U-shape having parallel upright legs, the legs of said movable member overlapping the corresponding legs of the fixed member, a pin and slot connection between adjacent corresponding legs of the members, a multi-lamped socket member fixed to the fixed member between the legs and between the tops and bottoms of said members, a shade secured to the movable member, a nipple depending from the socket member and adapted to pass through the shade in the contracted position of the frame, a nut on the nipple in said position, the frame members, socket member and shade being in coaxial relation, means securing the shade to the movable member comprising a second nipple fixed to the movable member and having an opening therethrough for the passage

of the first mentioned nipple, the second nipple being shorter than the first mentioned nipple, a second nut on the second nipple clamping the shade to the movable member, a switch for and in fixed relation to the socket member, and a switch operating member passing through the first mentioned nipple and through the first mentioned nut.

2. In an electric lighting fixture, a multi-lamped socket member, a fixed reflector in upward spaced relation to the member, a shade in downward spaced relation to the member, means fixedly connecting the member and the reflector in coaxial relation, a frame comprising a fixed member of strip material and of inverted U-shape having a pair of upright rigid parallel legs integrally joined at the upper ends thereof by a web having a central opening therein, each leg having an upright slot therein terminating at a point in upward spaced relation to the lowest part of the leg, means fixing the fixed member to and in coaxial relation to the reflector and the socket member, a movable frame member of strip material and of U-shape having a pair of upright rigid parallel legs integrally joined at the lowest ends thereof by a web having a central hole therein, each of the legs of the movable frame member respectively overlapping the corresponding leg of the fixed frame member, a pin fixed to each of the legs of the movable member and entering the slot of the corresponding leg of the fixed member, means including an element passing through and fixed in the hole of the web of the movable member and passing loosely through the shade, to secure the shade to the last mentioned web, a nipple projecting loosely through said means and fixed to and in coaxial relation to the socket member, and a nut removably engaging the nipple and the shade-securing means when the movable member is in the uppermost position thereof at the upper part of the nipple, the nut thereby securing the shade positively in said position.

3. The fixture of claim 2, the element comprising a second nipple projecting downwardly through the shade and shorter than the first mentioned nipple, and the shade-securing means including a second nut engaging the second nipple under the shade and clamping the shade against the web of the movable frame member.
